UNITED STATES PATENT OFFICE.

VICTOR M. SALO AND JOHN RÜKONEN, OF CHICAGO, ILLINOIS.

MOTOR-BOAT.

No. 873,614.

Specification of Letters Patent.

Patented Dec. 10, 1907.

Application filed January 25, 1907. Serial No. 354,160.

To all whom it may concern:

Be it known that we, VICTOR M. SALO and JOHN RÜKONEN, subjects of the Emperor of Russia, residing at 135 East Chicago avenue, 5 in the city of Chicago, county of Cook, and State of Illinois, have invented certain new and useful Improvements in Motor-Boats, of which the following is a specification.

The object of our invention is to increase 10 the buoyancy and the speed of the boat.

The manner in which we accomplish our object is described in the following specifications and illustrated in the accompanying drawings in which:

15 Figure 1 is a side elevation, Fig. 2 is an underneath plan view, Fig. 3 is a top plan view, Fig. 4 is a stern end view and Fig. 5 is a stem end view.

In the drawings A indicates the main body 20 of the boat, A¹ is the open interior of the boat and A² the seats under which inclosures can be made for carrying articles of necessity. The ends A³ of the boat are constructed as tanks adapted to hold fluids for fuel and for 25 the purpose of increasing the buoyancy.

A⁴ is the stern and A⁵ the bow of the boat.

Built into the body of the boat is a fin keel B constructed of thin metal. The bottom edge B¹ of this keel tapers from a point under 30 the bow of the boat downward to a horizontal line beneath the propeller and ends with a step B² for the rudder post.

In the keel between the body A of the stern end of the boat and the bottom edge B¹ 35 is an oblong aperture B³ adapted to allow the free revolutions of the propeller E therein.

Extending from beneath the engine C in the forward part of the interior A¹ of the boat is a propeller shaft tube B⁴. This tube extends downwards and rearwards to the bearing B⁵. On the rear end of the keel and in line with the bearing B⁵ is a bearing B⁶. In this tube and in these bearings is a shaft D and D¹ coupled at D².

Supported on the part of the shaft D¹ between the bearings B⁵ and B⁶ is a propeller E consisting of the sleeve E¹ and blade E².

Pivotaly supported in the keel step B² is a rudder post F extending vertically through the stern of the body of the boat. To this 50 post the rudder F¹ is affixed.

The diagrammatic view Fig. 4 shows the shape of the body of the boat the vertical lines b¹ to b⁵ corresponding with the horizontal cross lines b¹ to b⁵ in Fig. 2 and the vertical lines a¹ to a⁴ in Fig. 5 corresponding with the cross lines a¹ to a⁴ in Fig. 2.

In this boat any form of motor and its connection with the propeller shaft may be used and any suitable form of coupling, bearing, 60 and means of affixing the propeller to the shaft and for operating the rudder may be used.

What we claim and desire to secure by Letters Patent is:

In a motor boat the combination consisting of a metallic fin keel tapering from the bow to a point below the propeller and from thence parallel with the water line to the stern, said keel having a step to support the 70 end of a rudder post, an opening to permit the rotation of the propeller therein, bearings to support the propeller shaft and a connecting shaft tube extending from one of said bearings diagonally upwards into the 75 hull; a propeller shaft supported in said bearings parallel with the water line; a propeller affixed on said shaft within the said opening in said keel; and a connecting shaft in said tube connected with said propeller shaft and 80 a motor in said boat.

VICTOR M. SALO.
JOHN RÜKONEN.
